UNITED STATES PATENT OFFICE.

SAMUEL J. WEBB, OF MINDEN, LOUISIANA.

COTTON-COMPRESS.

No. 828,002.

Specification of Letters Patent.

Patented Aug. 7, 1906.

Application filed June 19, 1900. Serial No. 20,888.

To all whom it may concern:

Be it known that I, SAMUEL J. WEBB, a citizen of the United States, residing at Minden, in the parish of Webster and State of Louisiana, have invented certain new and useful Improvements in Cotton-Presses, of which the following is a specification.

Heretofore in condensing or compressing cotton in rebaling the same it has been customary to introduce the plantation-bale between the platens of a press, to which power is so applied as to compress and condense the bale in the direction generally in which pressure was applied in the first instance in the formation of the plantation-bale. In other instances the plantation-bale has been compressed and condensed in the compression-press in the direction in which it was pressed in the plantation-bale and then compressed and condensed in a direction transverse to that in which the plantation-bale has been compressed. In all of these operations there are practically two compressions of the plantation-bale, and in the act of each compression power is applied to the maximum extent of the capacity of the press to condense the bale to the greatest practicable extent, and the pressure applied is over the whole area of the platens of the press.

My object is to avoid the necessity of two compressions of the bale, and in so doing I operate in the first instance upon the mass of cotton contained in the plantation-bale, so as to change the cross-sectional form without material or necessary compression and practically without any material pressure upon the plantation-bale, thereby reducing the area of the material subjected to the platens of the press, and, in fact, reducing the area of platen required, so that the power of the press being applied over a more limited area it secures a very much more extended pressure per square inch, and therefore a greater compression energy than would otherwise be available.

In carrying out my invention the apparatus may be made in different forms. I will now describe one which has proved to be effective, reference being had to the accompanying drawings, in which—

Figure 1 is a side elevation of a press embodying my improvements; Fig. 2, a sectional elevation of the same; Fig. 3, a side view illustrating a safety device connected

with the main and auxiliary engines; Fig. 4, an enlarged sectional elevation of the safety device. Fig. 5 illustrates a modification of the invention.

The frame A of the press is constructed in any suitable manner to support the upper platen B, which is preferably the fixed platen, although the lower platen C may be fixed, or both may be movable.

The movable platen is operated from a steam-cylinder D, the piston 1 of which is provided with a cross-head 2, carrying two pins 3 3, to each of which is connected a link 4, pivoted by a pin 5 to a link 6, which latter is connected by a pin 7 to the upper end of the connecting-rod 8, pivoted at 9 to the lower platen. The pin 5 is carried by a link 10, which is pivoted at 12 to the frame of the press, and the pin 7 by links 31, connected at 30 to the frame. I do not herein claim this combination of links, which serve as a means of securing first an extended movement of the lower platen when a slight pressure is applied and then a more limited movement and increased leverage to secure a very high degree of pressure, as this is set forth in my application, Serial No. 720,850, filed June 16, 1899. So far as my present invention is concerned, however, it is immaterial in what manner one platen is brought toward the other or how they may be brought together and separated, as my invention may be used in connection with any suitable character of press for this purpose, and I will therefore not here more fully describe the details of the press shown.

The lower and the upper platen may both be of the same area, but I prefer to combine my appliances in the form of an attachment to a press having an upper platen B of the full area of the plantation-bale and a lower platen C of more limited area corresponding to that to which the form of the bale is changed, so that if it is desired to convert the apparatus into one operating with both platens of the full area of the plantation-bale this may be done by removing the attachment and substituting a wider lower platen-plate for the one employed in connection with the attachment. This attachment comprises two pivoted plates E E with their pivots 14 opposite the edges of the lower platen-plate, so that when the two plates E E are turned down to a horizontal position the plantation-

bale may extend over the hinges of the same, as shown in dotted lines *y*.

When the platens are at their maximum distance apart, the distance between them is considerably greater than the height of the bale—say twelve inches, more or less—so that when the plates *E E* are turned from a horizontal to a vertical position the particles of cotton in the plantation-bale will be so displaced as to alter the form of the bale practically without compressing it, so that it is reduced in lateral dimensions to a thickness corresponding to the width of the lower platen-plate—say eighteen inches—but the surplus cotton is displaced toward the top, so that the height of the bale is increased, for instance, between the platens, say, to five feet, there being no substantial increase in the density of the bale. It will therefore be noted that the plates *E E* are not platens or compressing-plates, but are simply displacing-plates, which displace the particles of cotton without materially compressing or condensing the same. When these plates are turned up to the vertical position, they are retained in that position while the cotton is compressed between the platens. In the construction shown this is accomplished by the upward movement of the lower platen, which is brought toward the upper platen to the greatest possible extent, and the bands are then passed through the grooves of the platens (after lowering the plates *E*) and secured, thus banding the compressed bale, which is therefore reduced to its most limited bulk and greatest density by a single pressure in one direction and without any other manipulation.

The displacing-plates while preferably hinged, as they thereby tend to more effectually displace the cotton upward toward the space between the platen and the top of the bale, are not necessarily hinged, but may be moved out and in laterally, especially when the bale is introduced from the end of the press. Thus, as shown in Fig. 5, there are two plates *E E'*, which can be moved toward and from the space between the platens by the action of a motor fluid in two cylinders *I I*, each having a piston 37, connected with a rod 38, connected to one of the plates, the motor fluid being admitted through pipes 39, controlled by proper valves.

When it is desired to employ the press for ordinary baling purposes, applying pressure to the entire surface of the plantation-bale, the upper platen is of the full width shown in the drawings. When, however, it is desired to use the press only in the manner before described, the face of the upper platen will be of the same width as that of the lower platen. In order to adapt the press to these changes, the platen-plates *a a* may be detachable and separate from the supporting parts, as shown, being bolted thereto by bolts secured in any suitable manner.

As before stated, for baling in the ordinary manner the narrow plates are taken off and wide plates substituted therefor.

While the displacing-plates *E E* may be operated in any suitable manner, I preferably make use of an engine *F* for each plate, comprising a cylinder *f*, with a piston 16 and piston-rod 17, connected to a cross-head 18, moving upon suitable guides 19, connected by connecting-rods 20 to a cross-pin 21, connected by a link 22 to the plate *E*, the cross-pin being also connected to links 23, the links being so proportioned that the links 23 22 practically constitute a toggle to secure sufficient power to insure the displacement of the mass of cotton when the plates are brought to a vertical position and also when in line with each other to act as a positive abutment to resist the lateral pressure of the cotton when the mass is being condensed between the platens. To properly support the toggles against this pressure, I make use of tie-rods 25 26, meeting at the pins 27, to which the links 23 are pivoted, the said tie-rods 26 extending diagonally upward and being bolted to the frame of the press, while the tie-rods 25 extend across the press between the two pins 27, forming a yoke.

Any suitable arrangement of pipes and valves may be employed for conducting the motor fluid to the cylinders of the engines and discharging the same therefrom.

It is very desirable to avoid the possibility of pressure being applied to lift the plates *E* when the latter are down and the workmen are engaged in banding the bale which is compressed between the two platens. To avoid this, I combine with the engines and operating connections of the plates *E* a safety device consisting of a pressure-regulator *G*, so arranged that so long as there is pressure beneath the piston in the main cylinder *D* steam cannot flow to the cylinders of the engines *F*. As shown in Figs. 4 and 5, the steam-pipe 30 passes to casing 31 of the regulator *G*, which has a valve 32, controlling the flow of steam from the pipe 30 to the pipes 33 34, leading to the ends of the cylinders of the engines *F*. The valve 32 is connected to the regulator-piston 35, and the space above the latter communicates through a pipe 36 with the space below the main piston of the main cylinder *D*, so that so long as there is pressure below the main piston the valve 32 will be maintained in its place and the pistons of the engines *F* cannot be elevated.

Without limiting myself to the precise construction and arrangement of parts shown, I claim as my invention—

1. A compress provided with platens, displacing-plates, and means for carrying them toward a plantation-bale between the platens to displace the material of said bale and change the form thereof making the bale nar-

rower prior to the compressing action of the platens, substantially as set forth.

2. A compress provided with a platen having a face corresponding to the width to which a plantation-bale is to be reduced, displacing-plates arranged to act laterally upon said bale to displace the contents and alter the form thereof without compressing the same, and means for retaining the plates in position and for operating the platens to compress the bale between such plates, substantially as set forth.

3. A compress provided with platens, means for separating them to a greater extent than the height of a plantation-bale, displacing-plates for operating upon the sides of the bale to displace the contents thereof making the bale narrower between the platens but without compressing the same, and means for retaining said plates in position during the compressing action of the platens, substantially as set forth.

4. The combination with the platens of a compress, of displacing-plates, and means for bringing them against the sides of a bale to alter the form thereof without compressing it, substantially as set forth.

5. The combination with the platens of a compress, of displacing-plates, and means for carrying them toward the plantation-bale between the said plates to reduce the area of the bale subjected to the action of the platens, substantially as set forth.

6. In a compress, means for reducing the area of a surface of a bale, and means for compressing the bale by applying pressure to the reduced surface, without shifting or turning the bale, substantially as set forth.

7. In a compress, means for reducing the dimensions of a bale in one direction to present opposite faces of reduced area, and means for applying pressure to said faces while the bale remains in its position, substantially as set forth.

8. The combination in a compress, of a narrow and a wide platen, and displacing-plates, the narrow platen having a narrow pressing-face adapted to work between the displacing-plates when they are in closed position and a wide pressing-face adapted to be applied to the narrow platen to press bales when the displacing-plates are not used, substantially as set forth.

9. The combination with the platens of a compress, of displacing-plates hinged to the frame of the press, and engines connected to the said plates to carry the same to and from the space between the platens, substantially as set forth.

10. The combination with the platens of a compress, of hinged displacing-plates, toggles arranged to be in line when the plates are elevated, and engines connected to operate said toggles, substantially as set forth.

11. The combination with the platens and

frame of a compress, of displacing-plates hinged to said frame, toggle-links 23 swinging upon pins 27, connected by tie-rods to the said frame and connected by links 22 to the displacing-plates, and engines for operating the toggle-links, substantially as set forth.

12. The combination in a compress and with the platens and operating-engine therefor, displacing-plates, operating-engines 75 therefor, and connections, of a valve controlling the flow of motor fluid to the engines operating the displacing-plates, and means for maintaining the valve in its seat by the pressure beneath the main piston, substantially as set forth.

13. The combination with the platens of a compress, of hinged displacing-plates and toggles arranged to come practically in line when the plates are elevated so as to form 85 the necessary rigid abutment to hold the plates in closed position while the bale is being compressed between them, substantially as set forth.

14. The combination with the platens of a compress, of displacing-plates and means for operating them and for holding them rigidly in closed position while the bale is being compressed between them.

15. In a compress, the combination of 95 plates arranged to operate against the sides of a bale to narrow it, and means for compressing the bale while it is confined between the said plates.

16. In a compress, the combination of side 100 plates arranged to press the bale in one direction, means for operating said plates, means for holding said plates in their closed position, and means for compressing the bale in a transverse direction while thus confined between the plates.

17. In combination with a compress, plates or sides hinged to a stationary part of the press, and means for moving them to and from the space between the platens of the 110 press.

18. In combination with a compress, plates or sides swinging on stationary hinges, and means for swinging said sides to and from the space between the platens of a press.

19. The combination with the platens of a compress, of hinged displacing-plates, and means for swinging the latter toward the space between the platens with increasing power, substantially as set forth.

20. The combination in a compress, of means for reducing the bale in one direction and retaining said reduction while the bale is being compressed, and platens for compressing the bale.

21. In a compression-press, the combination of two platens of different widths, means for compressing a bale to and retaining it of a thickness corresponding to the width of the narrow platen, and means for operating the 130

platens to compress the bale while so retained, substantially as set forth.

22. A compression-press having plates or sides movable to form the sides of a compression-chamber, a stationary platen having its working face wider than the space between the plates when they are in closed position, and a second platen having its working face narrower than the distance between the said side plates when they are in closed position, substantially as described.

23. A compress having sides or plates hinged at stationary points and adapted to form a compression-chamber, and platens, one of which is stationary and of greater width than the space between the plates when they are in closed position.

24. A compress having sides or plates hinged at stationary points and adapted to form a compression-chamber, and platens, one of which is movable and has a working

face narrower than the distance between the said plates when they are in closed position, substantially as described.

25. The combination with a compress, of 25 plates or side pieces, each swinging on a stationary hinge and adapted to form sides of a compression-chamber into which the bale may be compressed.

26. The combination with a compress, of 30 plates or side pieces, each swinging on a stationary hinge and adapted to form sides of a compression-chamber into which the bale may be compressed, and means for operating said plates, substantially as set forth. 35

In testimony whereof I have signed my name to this specification in the presence of two subscribing witnesses.
